Primary Examiner—Wallace R. Burke*Assistant Examiner*—Melody Brown*Attorney, Agent, or Firm*—Terry M. Gernstein[57] **CLAIM**

The ornamental design for a ground effect emergency transport vehicle, as shown and described.

DESCRIPTION

FIG. 1 is a perspective view of a ground effect emergency transport vehicle showing my new design;

FIG. 2 is a front elevational view thereof;

FIG. 3 is a rear elevational view thereof;

FIG. 4 is a side elevational view thereof, the side opposite being a mirror image of the side shown in FIG. 4;

FIG. 5 is a top plan view thereof; and,

FIG. 6 is a bottom plan view thereof.

FIG. 1.

FIG. 3.

FIG. 2

FIG. 4.

FIG. 6.

FIG. 5.
